UNITED STATES PATENT OFFICE.

CHARLES W. LOGAN, OF KENMORE, NEW YORK, ASSIGNOR TO MARKEL ELECTRIC PRODUCTS, INC., OF BUFFALO, NEW YORK, A CORPORATION OF NEW YORK.

DESIGN FOR A CHANDELIER.

Application filed November 23, 1928. Serial No. 29,016. Term of patent 3½ years.

To all whom it may concern:

Be it known that I, CHARLES W. LOGAN, a citizen of the United States, residing at Kenmore, in the county of Erie and State of New York, have invented a new, original, and ornamental Design for a Chandelier, of which the following is a specification, reference being had to the accompanying drawing, forming part thereof.

In said drawing:

Figure 1 is an elevation of a chandelier embodying my new design.

Figure 2 is a bottom plan view showing a segment of the applied ornamentation which is repeated throughout the area of the base of the chandelier.

I claim:

The ornamental design for a chandelier, substantially as shown.

CHARLES W. LOGAN.
